UNITED STATES PATENT OFFICE.

WILLIAM BARBER, OF LONSDALE, RHODE ISLAND, ASSIGNOR TO DRAPER COMPANY, OF HOPEDALE, MASSACHUSETTS, A CORPORATION OF MAINE.

WEAR-PROTECTING MEANS FOR HEDDLE-BARS.

SPECIFICATION forming part of Letters Patent No. 732,033, dated June 30, 1903.

Application filed April 14, 1903. Serial No. 152,597. (No model.)

To all whom it may concern:

Be it known that I, WILLIAM BARBER, a citizen of the United States, and a resident of Lonsdale, county of Providence, State of Rhode Island, have invented an Improvement 5 in Wear-Protecting Means for Heddle-Bars, of which the following description, in connection with the accompanying drawings, is a specification, like letters on the drawings 10 representing like parts.

This invention relates particularly to the so-called "steel-harness" type of loom-harnesses, wherein a series of steel heddles, serving also as warp-stop-motion detectors, are 15 mounted upon a transverse supporting-bar forming a part of the harness-frame. A loom-harness of this type is shown in United States Patent No. 536,969. The detector-heddles, formed of thin flat metallic strips, are provided 20 with elongated slots, through which the supporting-bar, also metallic, is passed, the heddles having a limited movement longitudinally relatively to the bar. In actual practice the heddle motion very frequently wears 25 the supporting-bar to such an extent that it must be discarded and a new one substituted, involving expense, as well as loss of time. On account of the contraction in width of the warp from the warp-beam to the fell the greatest 30 wearing motion of the heddles is manifest at the end portions of the heddle-bar, and ordinarily the wear is at the lower edge of the bar. In weaving some goods the wear is more apparent on the upper edge or top of 35 the bar, due to certain conditions of tension. In either case, however, the edge of the bar is subjected to the wear; and it is the object of my present invention to provide simple and removable means for protecting the heddle- 40 bar from such wear, so that such means can be renewed whenever necessary without necessitating any change in the heddle-bar. By thus providing protection for the latter its life is lengthened indefinitely and the 45 wear which results from the heddle motion is taken up by cheap and easily-renewed protecting means.

Figure 1 is a front elevation, centrally broken out to economize space, of a sufficient 50 portion of a steel harness-frame to be understood, with one embodiment of my invention

applied thereto. Fig. 2 is a transverse sectional view thereof on the line 2 2, Fig. 1, looking toward the left; and Fig. 3 is a perspective view of the clamping members detached illustrated in Figs. 1 and 2.

The side bars *a* of the harness-frame, having at their upper ends heads *a* ^x, provided with seats for the heddle-supporting bars *b* *b*, and having extensions *a*', to which are secured the usual overhead connections *c* ^x, may be and are of substantially well-known construction, the heddle-bars being held in place by bolts *b* ^x.

I have shown a frame arranged for a double bank or series of detectors, one bar *b* for each bank, the bars being made of rather thin flat metal set on edge. (See Fig. 2.) The bars pass through elongated slots *d* ^x in the detectors *d*, made usually as thin flat 70 strips of steel, substantially as in the patent referred to, and having a limited longitudinal movement relatively to the bars.

In the drawings I have shown a piece of wire *p*, located below and adjacent the lower 75 edge of each heddle-bar and at each end thereof, the length of each piece depending upon the extent of the bar which requires protection. To removably secure each wire in place, I have devised a simple and effective clamp, 80 and herein each clamp holds the wires which constitute wear-receiving means at one end of the two heddle-bars. Each clamp consists of two like and preferably rectangular metal blocks *f* and *g*, grooved, respectively, on one 85 face to present two parallel channels *f*' *g*', Fig. 3, and holes *f* ^x and *g* ^x are made in the blocks between the channels. The block *f* is placed on top of the two bars *b*, the upper edges thereof entering the channels *f*', and 90 the block *g* is brought up below the bars, so that the lower edges thereof enter the grooves *g*', as shown best in Fig. 2, and a headed bolt *h* is passed through the holes in the two blocks between the heddle-bars. A nut *h*' and washer 95 *h* ^x are applied to the threaded end of the bolt, and by setting up the nut the blocks *f* and *g* are drawn toward each other. Before so doing, however, the outer ends of the two wear-receiving members *p* are inserted in the channels or seats *g*', between the bottoms of said channels and the edges of the bars, and then 100

the nut is set up, tightly clamping the said members p in position against the edges of the heddle-bars.

Referring to Fig. 1, it will be seen that the 5 clamps are located adjacent the heads a^x and the wear-receiving members p extend inward as far as desired, usually only a few inches. Preferably the members p are made of straight pieces of cheap wire of proper diameter, and 10 they take up all the wear due to the heddle-motion and the action of the ends of the heddle-slots d^x , effectually protecting the bar b . When a wire becomes worn, it is removed by loosening the nut h' and a new one is inserted. 15 Manifestly such wires could be placed over and adjacent the top edges of the heddle-bars, if desired, or they could be used at both top and bottom if the wear required such use. Herein I have shown the channels g' as 20 deeper than the channels f' , as the wear-receiving members are seated in the channels g' ; but it is within the spirit and scope of my invention to deepen the channels f' if top

protection is needed or to reverse the location of the blocks, placing block f below and 25 block g above the heddle-bars.

Having fully described my invention, what I claim as new, and desire to secure by Letters Patent, is—

In a harness-frame, a transverse heddle-supporting bar, metallic heddles slotted to receive said bar and having longitudinal movement relatively thereto, a clamp on the bar at each end thereof, and an elongated wear member removably held by each clamp and 30 extended inward along the edge of the bar, to protect the same from wear due to heddle-motion.

In testimony whereof I have signed my name to this specification in the presence of 40 two subscribing witnesses.

WILLIAM BARBER.
